INVENTOR

Alonzo H. Weston
BY Frederick S. Duncan
ATTORNEY

UNITED STATES PATENT OFFICE.

ALONZO H. WESTON, OF YONKERS, NEW YORK, ASSIGNOR TO AMERICAN CHAIN COMPANY, INC., A CORPORATION OF NEW YORK.

GUARD RAIL.

Application filed June 30, 1922. Serial No. 572,102.

To all whom it may concern:

Be it known that I, ALONZO H. WESTON, a citizen of the United States, residing at Yonkers, in the county of Westchester, State 5 of New York, have invented certain new and useful Improvements in Guard Rails, of which the following, taken in connection with the accompanying drawings, is a specification.

10 One object of the invention is to provide a one-piece guard rail, that is to say, a guard rail composed of a rail portion proper and a base which extends beneath the main rail.

Another object is to provide a one-piece 15 guard rail of such character that lateral stresses thereon such as are ordinarily encountered under service conditions will be resisted by the traffic rail.

Another object is to provide a combined 20 one-piece guard rail and support of such character that lateral stresses thereon will be borne by the traffic rail, but which is also provided with means for maintaining the guard rail at a uniform distance from the traffic rail and for insuring that in adjustment the guard rail will be spaced at an unvarying predetermined distance from the traffic rail.

Another object is to provide a guard rail 25 which is provided with means for predetermining the distance at which it shall be located from the main rail, and which shall also contain provision for taking up the wear ordinarily incident to use.

30 Referring to the drawings:

Figure 1 is a plan view of the guard rail shown in association with a traffic rail.

Figure 2 is an enlarged view of a portion 35 of the guard rail shown in association with a traffic rail.

Figure 3 is a fragmentary view in elevation of the guard rail.

Figure 4 is a view in section on the line 40 4-4 of Figure 2.

Figure 5 is a view in section on the line 45 5-5 of Figure 2.

Figure 6 is a view in section on the line 50 6-6 of Figure 2.

The guard rail is shown in association 55 with a traffic T-rail of conventional form consisting of the tread 1, the web 2, the inner flange 3 and the outer flange 4.

The guard rail rests upon end base plates 5-5 and also a number of intermediate base plates 6, which are preferably spaced in accordance with the spacing of the cross ties of the road bed and which, if desired, may be integral with the guard rail and be adapted to extend beneath the traffic rail, so that the latter may rest thereon. For lightening 60 the guard rail it may be made hollow as shown in Figures 4, 5 and 6 and it may comprise the outer side wall 7 and the inner side wall 8, these side walls being erected on the bases 5 and 6 and supporting the head 6^a. 65 As observed in plan view the shape of the guard rail as shown in Figures 1 and 2 is such that the ends diverge from the traffic rail inwardly toward the middle of the track, the space between the diverging portions and the traffic rail near the ends being taken up by foot guards 9.

In order to make it possible to renew from time to time the wearing surface of the guard rail, I prefer to provide a wearing 70 strip 10 retained against the head of the guard rail by the bolts 11 or any other convenient means.

The effect of a side thrust of the wheels 75 of a passing train against the wearing strip 80 is such that a strong shearing thrust tends to be set up in the base plates along their lines of contact with the edge of the traffic rail. In order to prevent this shearing stress from becoming extensive, I provide the 85 brackets 12 projecting from the outer wall 7 of the guard rail and having a shoulder 13 which extends beneath the tread of the traffic rail leaving a slight clearance between the shoulder and the traffic rail as shown in Figures 4, 5 and 6, and shoulder 14 which extends toward the upper surface of the flange 3, also in like manner leaving a slight clearance between the shoulder and the traffic rail.

Accordingly a side thrust against the wearing strip 10 tends to lift the brackets 12 and after the clearance between the shoulder 13 and the under side of the tread 1 has been taken up, further thrust is resisted by the 90 downward pressure of the tread 1 on the shoulder 13. In a similar manner, any side thrust against the inner side of the traffic rail is opposed by the shoulder 14 after the 95

clearance between that shoulder and the flange 3 has been taken up. Under ordinary circumstances, however, the shoulder 14 functions in this manner very infrequently 5 and to a very limited extent.

The value of providing clearance between the shoulders 13 and 14 and the opposing portions of the traffic rail lies in the fact that there is thus provided a considerable 10 change of adjustment to take care of non-uniformity in proportions and dimensions of traffic rails. In order, however, to insure that there shall be a uniform distance under all circumstances between the guard rail 15 and the traffic rail, I prefer to provide stop lugs 15-15, projecting from any suitable portion of the guard rail, for example, from the part 9, the length of the lugs being such as to establish a minimum spacing of the 20 guard rail with respect to the traffic rail. The number of these lugs is not invariable, but I find that two of them usually answer the purpose satisfactorily. The presence of these lugs thus dispenses with any necessity 25 for estimating the proper location of the guard rail with respect to the traffic rail, this distance being uniformly and invariably fixed by the extent to which the lugs project. The consequence is that the guard 30 rail may not only be initially placed at the proper distance, but it will maintain that distance under all circumstances, with the exception of such change as may arise from wear on the wearing strip 10 which is of little consequence, at any rate provided the 35 wearing strip be renewed from time to time as required.

In order to make the structure adaptable for traffic rails of varying width of base 40 flange, I provide the base plates with apertures 16 stepped as shown in Figures 1 and 2 in such manner as to permit the placing of rail spikes at a suitable range of varying distances on the cross ties.

45 Having thus described my invention, I claim:

1. In a guard rail structure, a guard rail, means for causing the traffic rail to oppose lateral thrusts on the guard rail and a stop 50 adapted to limit the proximity of the said thrust opposing means to the traffic rail.

2. In a guard rail structure, a guard rail, a bracket projecting laterally from said guard rail and adapted to extend toward the 55 under side of the tread of a T traffic rail and a stop projecting from said guard rail and adapted to abut against said traffic rail and adapted to limit the proximity of the said bracket to the traffic rail.

60 3. In a guard rail structure a guard rail and a bracket projecting laterally therefrom, said bracket being formed to present a shoulder toward the underside of the tread of a traffic rail, said guard rail being also 65 provided with a stop adapted to space the

guard rail and traffic rail at such distance as to leave slight clearance between said shoulder and said tread.

4. In a guard rail structure, a guard rail, a bracket projecting laterally from said guard rail and adapted to extend toward the under side of the tread of a T traffic rail, two shoulders on said bracket, one adapted to extend toward the under side of the tread of the traffic rail and the other adapted to 70 extend toward the upper surface of the flange of said traffic rail and a stop extending from said guard rail and adapted to abut against said traffic rail and also adapted to establish a minimum spacing of said 75 guard rail with respect to said traffic rail, said spacing being such that there is slight clearance between the said shoulders and said traffic rail.

5. In a guard rail structure, a guard rail, 80 means for causing the traffic rail to oppose lateral thrusts on the guard rail, a stop for establishing a minimum spacing of the thrust opposing means with respect to the traffic rail and a detachable wearing strip on 90 said guard rail.

6. In a guard rail structure, a guard rail, a bracket projecting laterally from said guard rail and adapted to extend toward the under side of the tread of a T traffic rail, 95 a stop projecting from said guard rail and adapted to abut against said traffic rail and to prevent contact of said bracket with the traffic rail and a detachable wearing strip on said guard rail.

7. In a guard rail structure, a guard rail, a bracket projecting laterally therefrom, said bracket being so formed as to present a shoulder toward the under side of the tread of the traffic rail, said guard rail being also 105 provided with a stop adapted to establish a minimum spacing between said shoulder and said traffic rail, said spacing being such as to leave slight clearance between said shoulder and said tread and a detachable 110 wearing strip on said guard rail.

8. In a guard rail structure, a guard rail, a bracket projecting laterally from said guard rail and adapted to extend toward the under side of the tread of a T traffic rail, two shoulders on said bracket, one adapted to extend toward the under side of the tread of a traffic rail and the other adapted to extend toward the upper surface of the flange of said traffic rail, a stop projecting from 115 said guard rail and adapted to abut against said traffic rail and to establish a minimum spacing between said guard rail and said traffic rail, and said traffic rail and said spacing being such as to leave slight clearance 120 between said shoulders and said traffic rail and a detachable wearing strip on said guard rail.

9. In a guard rail structure, a plurality of base plates, a guard rail erected on said base 130

plates, the said base plates being adapted to lie on cross ties and to extend beneath and support a traffic rail, means for causing the traffic rail to oppose lateral thrusts on the 5 guard rail and a stop for establishing minimum spacing between the thrust opposing means and the traffic rail.

10. In a guard rail structure, a plurality of base plates, a guard rail erected on said 10 base plates, said base plates being adapted to extend beneath and support a traffic rail, brackets laterally projecting from said guard rail, said brackets having shoulders adapted to extend toward the under 15 side of the tread of the traffic rail and also toward the upper surface of the flange of the said traffic rail, a stop lug on said guard rail adapted to abut against the said traffic rail and also adapted 20 to establish a minimum spacing between the said guard rail and said traffic rail, the said

spacing being such as to leave slight clearance between said shoulders and said traffic rail.

11. In a guard rail structure, a plurality 25 of base plates, a guard rail erected on said base plates, said base plates being adapted to extend beneath and support a traffic rail, brackets laterally projecting from said guard rail, said brackets having shoulders 30 adapted to extend toward the under side of the tread of the traffic rail and also toward the upper surface of the flange of the said traffic rail, a stop lug on said guard rail adapted to abut against the said traffic rail 35 and also adapted to establish a minimum spacing between the said guard rail and said traffic rail, the said spacing being such as to leave slight clearance between said shoulders and said traffic rail and a wearing strip 40 on said guard rail.

ALONZO H. WESTON.
